UNITED STATES PATENT OFFICE

FITZ WILLIAM SARGENT, OF MAHWAH, NEW JERSEY, ASSIGNOR TO THE AMERICAN BRAKE SHOE AND FOUNDRY COMPANY, OF WILMINGTON, DELAWARE, A CORPORATION OF DELAWARE

BRAKE SHOE

Application filed November 17, 1930. Serial No. 496,061.

This invention relates to brake shoes of the kind which are provided at the back with an embedded reenforce plate or strip and which has for its object to prevent the back from breaking after the body of the shoe has fractured and to hold the parts of the body together until it is worn out.

Brake shoes are made of standard curvature to fit standard wheels, but due to wear of the tread of wheels there is often a variation between the curvature of the face of the shoe and the curvature of the tread of the wheel to which the shoe is applied, resulting in the body of the shoe fracturing under 5 brake application. Fractures of the body may also result from expansion and contraction of the body due to heat conditions, and while these fractures may be slight at first they do develop into cracks because of 10 the conditions to which brake shoes are subjected in service. The steel reenforce back is intended to hold the parts of the body together when it fractures or cracks and it usually suffices for this purpose, provided the rate of 15 shoe wear exceeds the fatigue limit of the steel back which is flexed under brake application at the crack in the body and also by the shoe flapping in its support and rubbing against the wheel when the brake is in release. Continued flexure of the back at the 20 crack in the body will cause excessive fatigue of the steel back at this point if the back is held rigidly in the body adjacent to the crack. In case of slow wear of the brake shoe 25 due to infrequent brake applications the back will break because of this constant flexure and the lower end of the shoe will fall away before the shoe is worn to the limit of wear. This happens more often on freight cars, 30 where the rate of wear is low due to light and infrequent brake applications, by continued vibration and flapping of the broken shoe against the wheel. It happens less often on 35 passenger cars where the breaking is more severe and frequent and the rate of wear of the shoe is more rapid so that the shoe is worn to the limit of wear before the steel back is destroyed by fatigue vibration. If the flexure of the back is extended over an appreciable length thereof, instead of being confined

to the immediate location of the crack, as would be the case if the back is held rigidly in the body throughout its length, the fatigue period of the steel back will be materially lengthened and under all ordinary conditions, according to my long experience and close observation, the back will hold the parts of the body together until the body has worn out in service without the back breaking.

The object of my invention is to insure the body of the shoe breaking at certain predetermined locations with reference to a part of the back which is free from rigid connection with the body so that the flexure of the back will be distributed over a considerable part of the back to prolong the fatigue period beyond the time required under usual conditions for wearing the body of the shoe down to the limit of wear.

And my invention also has for its object to provide that the middle portion of the back under and adjacent to the attaching lug shall be free from rigid connection with the body, including the lug, and further to insure that the body will crack transversely at or about the limits of the loose portion of the back so that the middle portion of the body will be free from rigid connection with the back but will be retained thereon by that portion of the body which comprises the attaching lug, and the flexure of the back in service will be distributed throughout the loose part thereof which will prolong the fatigue period until after the time required for completely wearing the body of the shoe to the limit of wear.

In the accompanying drawings I have illustrated the invention in a simple form of car shoe and referring thereto

Fig. 1 is a side elevation of the shoe.

Fig. 2 is a top plan view of the shoe.

Fig. 3 is a bottom plan view of the shoe.

Fig. 4 is a transverse sectional view on the line 4—4 of Fig. 2, and

Fig. 5 is a transverse section through the middle of the attaching lug and showing a wider key opening.

Referring to the drawings, 6 is the body of the shoe and 7 is the steel reenforce plate back which is embedded in the body at the

back thereof. A steel lug strap 8 is engaged with the back 7 and is partly embedded in the projections 9 of the body which form with the strap 8 the attaching lug of the shoe. Grooves or kerfs 10 are provided in the sides and face of the body at opposite sides of the attaching lug. These grooves are preferably parallel, or substantially parallel, and they are located at opposite sides of the attaching lug and at such points as may be determined upon for the body to crack. Between the grooves the back is free from rigid connection with the body. The body is cast on the back and that part of the back which it is desired shall be free from rigid connection with the body is coated with heat resisting material previous to the casting operation to prevent fusion of the cast body metal with the back in the casting operation. Ordinarily the projections 9 completely embed the sides of the strap 8 (Fig. 4) and project over the side edges of the back 7 which is cut away at 11 at the attaching lug. Instead of coating the back at the middle portion thereof to prevent it from fusing with the body metal, or in addition to the coating, I may make the key opening 12 of the attaching lug wider as shown in Fig. 5 by reducing the size of the projections 9 so that they will not overlap the narrow middle part of the back and this part of the back will be free so that it can flex over a considerable area. While it is desired that the loose intermediate portion of the back should extend over that portion of the shoe between the grooves 10 it is not necessary that there should be absolute coincidence between the grooves and the outer limits of the loose portion of the back. I prefer, however, that the loose portion of the back should generally and approximately extend from one groove to the other and not extend materially beyond the grooves, for what I consider to be the best commercial results, although it would not detract from my invention if the loose part of the back does extend beyond the grooves. In such case, if those parts of the body between the grooves and the ends of the shoe crack and the back is loose in any of the cracked parts, the dovetail connection between the body and the back at the edges of the back 13 must be relied upon to hold these parts in place in the shoe. It is for this reason I prefer to limit the free part of the back to approximately the limits formed by the grooves in the body. This may be provided for, if occasion requires, by prolonging the free portion of the back and locating the grooves farther apart than is shown in the drawings.

In practice the body of the shoe will crack very early in its use in the grooves 10 and since the back is free from rigid connection with the intermediate part 14 of the body between the grooves the back will be free to

flex for a considerable part of its length while the intermediate part of the body is held in place by the attaching lug, the projections 9, 9 of which are an integral part of the intermediate part of the body. With the body cracked at the grooves and the back free from rigid connection with the body and the lug intermediate of the grooves, any vibration imparted to the back while the shoe is hanging free from the wheel and any flexure of the back due to brake application will be distributed over the entire area of the free part of the back. If the back were held rigid in the body throughout its length and the body cracked on one or both sides of the attached lug, the vibration and flexure of the back would be confined to the line of the back coincident with the crack; and with the vibration so confined the fatigue period would be comparatively short. Whereas if the back is free from rigid connection with the body over a predetermined area so that the vibration effect will be distributed over this area the fatigue period will be correspondingly prolonged. I believe that if the free area is defined by grooves in the body at opposite sides of and comparatively close to the attaching lug it will be sufficient to prolong the fatigue period under average conditions until the body of the shoe is worn out. The provision of the grooves is important to insure that when the shoe fractures the cracks will occur at these predetermined locations which, at least in a general way, define the limits of that part of the back which is free from rigid connection with the body; and this intermediate part of the body is held in place by reason of the projections 9 and strap 8 which constitute the attaching lug of the shoe, so that even though this intermediate part is loose from the other parts of the body and is free from rigid connection with the back it will be held from dislodgement by its anchorage on the back and will perform the service expected of it.

I have shown the invention in a simple adaptation with the grooves located close to the attaching lug but the invention is not restricted to this particular type of brake shoe nor to the particular location of the grooves. I reserve the right to make all such changes in the form, construction and arrangement of parts of my invention as may be desirable to satisfy different conditions and within the scope of the following claims.

I claim:

1. A brake shoe comprising a body and a reinforce back, said back being secured to the body but having a portion thereof free from rigid connection with the body, and transverse grooves on the body corresponding substantially in location with the limits of said free portion of the back.

2. A brake shoe comprising a body and a reinforce back, said back being secured to

the body but having a portion thereof free from rigid connection with the body, transverse grooves on the body corresponding substantially in location with the limits of said free portion of the back, and means anchoring that portion of the body intermediate of the grooves and opposite the free portion of the back to the back for retaining said portion on the back when the body cracks on the lines of

10 the grooves.

3. A brake shoe comprising a body, a reinforce back, and an attaching lug, said back being secured to the body but having that portion thereof at the attaching lug free from rigid connection with the body, and transverse grooves on the body on opposite sides of and adjacent to the attaching lug.

4. A brake shoe comprising a body, a reinforce back, and an attaching lug, and 20 transverse grooves on the body at opposite sides of the attaching lug, said back being secured to the body but having that portion thereof between the grooves free from rigid connection with the body.

25 5. A brake shoe comprising a body, a reinforce back, transverse grooves on the body at opposite sides of the attaching lug, said back being secured to the body but having that portion thereof between the grooves free from rigid connection with the body, and an 30 attaching lug comprising projections from the body between said grooves and a lug strap embedded in said projections and interlocked with the back at said free portion.
